UNITED STATES PATENT OFFICE.

FREDERICK G. PROCTOR, OF DETROIT, MICHIGAN, ASSIGNOR TO PROCTOR-KEEFE COMPANY, OF DETROIT, MICHIGAN, A COPARTNERSHIP.

SLIDABLE CURTAIN FOR VEHICLES.

Application filed September 12, 1925. Serial No. 55,998.

My invention relates to slidable curtains for motor driven vehicles, and while more particularly designed for truck cabs is equally well adapted for other types of vehicles.

5 Vehicle curtains fitted with a flexible transparent window medium and secured to a window or door frame having resilient side rails, whereby they may slide in vertical and connecting overhead horizontal 10 channel guide rails are well known in the art.

Vehicle curtains have also been constructed of two opposing layers of fabric with registering window openings in which 15 are fitted sheet celluloid—the side marginal edges of the curtain being secured to the flexible side bars of a slidable frame, with an overlapping selvage strip folded into U-shaped form to cover the respective edges 20 of the frame and the curtain fabric.

It has been found however in practice that such a construction causes the inner portion of the selvage strip to "bunch up" when rounding the curve in the guide channels connecting the vertical channel with its overhead horizontal portion, thereby causing the curtain to bind with the result that it is often impossible to either raise or lower the curtain without employing considerable 25 force and effort which often results in the curtain being torn and the celluloid window broken.

30 And as a further result of the unequal drag and strain caused by the bulging of the selvage strip on its lower face and the inner side of the arc when "rounding" the curve of the channel rail it soon becomes worn at this point, thereby increasing the difficulty in raising and lowering the curtain when required.

It has also been suggested that metallic selvage strips be employed on one or both faces of the curtain at each side thereof—but this also has been found very objectionable due to the noise resulting from the edges of the curtain rattling in the grooves of the metallic guide rails in which they slide and which is greatly magnified when used in trucks employing a heavy spring suspension and the vibration of a heavy duty motor.

The purpose therefore of the present invention is to overcome these very objection-

able features and to further improve the construction of the curtains. 55

One object, therefore, of the present invention is to provide a curtain which may be constructed of one or more layers of fabric secured at their marginal edges to the flexible side rails of a frame slidable in vertical and horizontal overhead connecting guide channels—the marginal faces of the curtain and frame at each side being covered by two strips of fabric secured thereto by a line of stitching extending through said 60 strips and the curtain fabric—adjacent the edge of the flexible side rails of the frame. 65

By providing respectively two separate pairs of fabric strips at each side and face of the curtain to take the wear occasioned through raising and lowering the latter, the inner and outer strips of each pair readily conform to the difference in the arc produced by the curtain when bent in "rounding" the curve of the guide rail—thus the inner 70 strips are not distorted by the differences in the arcs of the respective outer strips and do not interfere with the free movement of the curtain when it is desired to raise or lower the same. 75

Devices employing a U-shaped marginal wearing strip overlapping the edges of the curtain and frame are also effected by atmospheric conditions causing the inner portion of the strip to swell and become distorted, 80 presenting a bulging surface which causes a great frictional drag upon the channel rail when it is desired to raise or lower the curtain. 85

These objectionable features are entirely 90 overcome in my invention by the employment of separate wearing strips secured to the inner and outer face of the curtain—the respective strips readily conforming to a variation due to atmospheric conditions 95 or differences between the arc of the inner and outer wearing strips of the curtain.

Furthermore as the greatest wear occurs at the inner marginal edge of the curtain when shifted from a vertical position to its 100 upper horizontal plane, or vice versa, the inner marginal strip may be readily removed when worn and replaced by a new strip at a nominal expense compared with that of a wide single U-shaped overlapping marginal 105 strip.

A further object in employing two strips of fabric in place of metallic strips is the elimination of noise due to the vibration of motor or jarring of truck when traveling over rough roads.

With the foregoing and other objects in view which will appear as the description proceeds the invention further resides in the combination and arrangement of parts and in the details of construction hereinafter described and claimed it being understood that changes may be made in the precise embodiment of the invention herein disclosed without departing from the spirit of the same.

15 In the drawings accompanying this specification:

Figure 1 is a fragmentary perspective view showing the cab and a portion of the body of a motor driven truck.

20 Figure 2 is a fragmentary perspective view through the cab showing one of the window curtains partially raised as when shifting the curtain from a vertical to an overhead horizontal position.

25 Figure 3 is a vertical cross-sectional view through the curtain and its supporting frame.

Figure 4 is a horizontal cross-sectional view through the curtain and its supporting frame showing fabric wearing strips covering the marginal inner and outer faces of the curtain—secured by a line of stitches extending through the marginal strips and edge of the curtain adjacent the flexible side rails of the window frame.

30 Figure 5 is a fragmentary elevation of the curtain and its supporting frame with parts broken away to show the respective layers of fabric forming the curtain, the inner and outer fabric wearing strips secured along one edge by a line of stitches extending through the curtain and wearing strips adjacent to the flexible side rails of the frame.

Referring now to the letters of reference 45 placed upon the drawings:

A denotes the cab of a motor driven vehicle.

B, B, designates channel rails secured to the vertical side frame of the cab and extending upwardly and thence in an overhead horizontal direction under the roof of the cab.

C represents a curtain slidable in said channel rails.

50 D indicates the curtain frame comprising a pair of flexible side bars E, E, connected by rigid cross-members F, F, secured to the side bars.

G, G, denote a fabric covering enclosing the frame and provided with suitable win-

dow opening H, in which is supported a flexible transparent medium I, for example sheet celluloid.

Covering the marginal edges of the fabric at each side of the curtain and overlapping its flexible side rails are strips of webbing J, J, secured to the curtain by a line of stitching j extending through the wearing strips and the curtain fabric adjacent to the flexible side rails of the frame.

K, indicates a suitable device for manually lifting the curtain secured to the lower edge of the latter, whereby it may be readily raised or lowered.

L, designates corner plates secured to the lower rigid transverse rail of the curtain and to the flexible side members.

Attention having been previously called to the advantages gained by employing separate fabric strips respectively placed on either side of the curtain at its marginal edge it will not be necessary to further enlarge upon this feature.

The fabric wearing strips serve to cushion vibration between the marginal edges of the curtain and its guide rails—thus deadening the noise which might otherwise occur due to the vibration of the vehicle or its motor;—and by employing separate strips the edge of the curtain presents a smooth even surface of uniform thickness throughout which readily adapts itself to the channel bars in which it is guided without danger of clogging therein.

Having thus described my invention what I claim is:

A slidable window frame having flexible resilient side rails and rigid transverse connecting bars; a fabric covering therefor, having window openings; celluloid windows fitted in the openings; a pair of selvage fabric strips respectively overlaying the margin of the fabric covering and each side of both of the flexible resilient side rails of the slidable frame, said fabric covering and said fabric strips being extended beyond the frame and having their outer marginal edges in flush relation, and the said fabric strips being secured to the fabric covering by a line of stitches adjacent the edge of the flexible resilient side rails, whereby folding of any fabric around the outside edges of the window frame is avoided and tendency of the fabric to bunch up and bind when rounding the curve of the channel groove is prevented.

In testimony whereof, I sign this specification.

FREDERICK G. PROCTOR.
